UNITED STATES PATENT OFFICE

BERNARD BRADFORD ROCKWOOD, OF LYONS, IOWA.

ROTARY ENGINE.

No. 905,371.

Specification of Letters Patent.

Patented Dec. 1, 1908.

Application filed May 7, 1908. Serial No. 431,459.

To all whom it may concern:

Be it known that I, BERNARD BRADFORD ROCKWOOD, a citizen of the United States, residing at Lyons, in the county of Clinton 5 and State of Iowa, have invented a new and useful Rotary Engine, of which the following is a specification.

This invention relates to rotary engines and more especially to that type of rotary 10 engine in which the rotor is actuated by reaction.

The object of the invention is to provide an improved general construction of such a device as well as to simplify the manner of 15 constructing the same and with as few parts as possible.

To that end, the invention consists of certain novel arrangements of parts and 20 combinations of details hereinafter fully described, illustrated in the accompanying drawings, and specifically set forth in the claims.

In the accompanying drawings like characters of reference indicate like parts in the 25 several views and; Figure 1 is a side elevation of a rotary engine constructed in accordance with this invention, a portion being broken away. Fig. 2 is a section through the center of such an engine taken at right 30 angles to Fig. 1, and in a vertical plane.

The engine consists substantially of a casing and a rotor. The casing comprises a cylindrical portion 10 provided with ends or heads 11. The ends or heads 11 are provided with suitable bearings 12 and 13. The 35 bearings 12 support a shaft 14 whereon is mounted a rotor 15. In the bearings 13 is held a hollow shaft 16 which serves as a steam pipe to convey steam to a steam chamber 17 centrally disposed in said rotor. A 40 suitable stuffing box 18 is provided to prevent the escape of steam around the hollow shaft 16. The rotor is of such size as to closely contact with the interior periphery 45 of the part 10 of the casing and is provided with a series of steam passages 19 leading from the steam chamber 17 to the periphery of said rotor. These steam passages are so arranged that the outer end of each is at an 50 acute angle to a tangent plane to the rotor at that point.

Around the inner periphery of the portion 10 of the casing is formed a series of pockets 20 sectoral in cross section. The center of 55 the arcuate portion of these pockets is preferably in the plane of the inner periphery

of the portion 10 and the straight portion is at an acute angle to a plane passing through that center and tangent to the inner periphery of said part 10. Exhaust pipes 21 preferably two in number and oppositely disposed are formed in the portion 10 and are branched as at 22 so as to connect with the chambers formed between the rotor and the casing end 11. 60

It is to be noted that the pockets 20 are longer than the width of the rotor so that the steam escaping through the passages 19 and into the pockets 20 may escape from these pockets into the spaces between the 70 rotor and the casing end 11, and then through the passages 22 into the exhaust pipe 21. 65

It is found advisable to make the passages 19 of less number than the pockets 20, and 75 it is further found advisable to make the ratio between the number of passages 19 and the number of pockets 20 a simple one such as 3 to 4, that being the one here shown. By reason of this there will be, in the present instance, but one-third of the passages 19 open to the pockets 20. This produces a considerable economy in the use of the steam. The number of pockets 20 and passages 19 may be varied at will and it will 80 be obvious that the more numerous these passages are the more powerful will the engine be. 85

In practice it is advisable to provide the hollow shaft 16 with a suitable throttle 90 valve, and in like manner it is advisable to provide the exhaust pipe 21 with a similar valve. These valves are not here shown as they do not form any part of this invention and may be of any desired form or shape. 95

It is obvious that minor changes may be made in the form and the proportion of the parts of this invention without departing from the principle thereof. It is not therefore, desired to confine the construction to 100 the exact form here shown, but it is desired to include all such as properly come within the scope of the invention.

What is claimed as new and desired to be secured by Letters Patent is:— 105

1. In a rotary engine, an outer casing provided with pockets around the interior periphery, a rotor mounted within and in spaced relation to the end of said casing, and provided with a centrally disposed steam chamber and outlets from the chamber to the periphery, each having its outer end at 110

acute angles to a plane tangent to the periphery at the center of the outlet, a steam pipe communicating with said chamber, and an exhaust pipe branched to connect to the spaces between the rotor and the end of the casing.

2. In a rotary engine, an outer casing provided with a series of sectoral pockets around the interior periphery, a rotor 10 mounted within and in spaced relation to the ends of said casing and provided with a centrally disposed steam chamber and an outlet from the chamber to the periphery, each having its outer end at an acute angle

to a plane tangent to the periphery of the 15 rotor and center of the outlet, said rotor being of less width than the sectoral pockets, a steam pipe communicating with said chamber and an exhaust pipe branched to connect to the spaces between the rotor and end of 20 the casing.

In testimony that I claim the foregoing as my own, I have hereto affixed my signature in the presence of two witnesses.

BERNARD BRADFORD ROCKWOOD.
